UNITED STATES PATENT OFFICE.

PAUL J. TIMBERLAKE, OF JACKSON, MICHIGAN.

HINGED DRYING FRAME.

Application filed July 14, 1926. Serial No. 122,378.

This invention relates to drying forms and more particularly to stocking drying forms of the type disclosed in my prior Patents #875,135, granted December 31, 1907, and 5 #1,493,294, granted May 6, 1924, and has for one of its objects to provide a device of this character which will be simple in construction, comparatively inexpensive to manufacture and more efficient in use than those here 10 tofore proposed.

A further object of the invention is to provide an improved hinge construction for such a drying form which may be inexpensively manufactured and assembled and which will 15 provide a frictional pivotal connection for the main elements of the form which will effectively hold them in any desired relative positions.

A still further object of the invention is to 20 provide a hinge construction for a drying form of the class described in which the parts are frictionally connected to maintain them in set angular positions while at the same time they are positively held against relative axial 25 or longitudinal movement so that the hinge will not become disconnected.

With the above and other objects in view which will appear as the description proceeds, the invention consists in the novel details of 30 construction and combinations and arrangements of parts more fully hereinafter disclosed and particularly pointed out in the appended claims.

Referring to the accompanying drawings 35 forming a part of this specification in which like reference characters designate like parts in all the views:

Figure 1 is a perspective view of the top portion of a drying form of the general type 40 shown in my said prior patents, showing one example of the improved hinge construction;

Fig. 2 is a top plan view of the parts shown in Fig. 1, a portion of the hinge element being 45 broken away;

Fig. 3 is a transverse sectional view taken approximately on the plane indicated by the line 3-3 of Fig. 2;

Fig. 4 is a fragmentary plan view of a 50 somewhat modified form of the invention;

Fig. 5 is a transverse sectional view of the form shown in Fig. 4, taken approximately on the plane indicated by the line 5-5 of the said figure; and,

55 Fig. 6 is a fragmentary perspective view of a still further modified form of the invention.

Referring more particularly to Figs. 1, 2 and 3 of the said drawings, the form comprises a pair of frames, 5 and 6, of loop construction, (only the upper portions of such frames being shown in Fig. 1,) which frames are preferably formed of wire, and of the same general character as those set forth in my said prior patents. The upper ends of the wires constituting the said frames are turned inwardly toward one another to provide in-turned end portions 7 and 8, respectively forming transverse members of the frames, and which end portions constitute each one element of a hinge. The other element is 60 formed of a sheet of metal 9, the opposite sides of which are rolled or stamped to provide substantially cylindrical loops 10 and 11 which receive the in-turned ends 7 and 8 of the frame members 5 and 6, respectively. 65

The in-turned ends 7 and 8 are provided respectively with grooves 12 and 13, see Figs. 2 and 3, extending around their peripheries intermediate their extreme ends and the bend, which joins them to the main body portions 80 of the frames, and the inner edges of the cylindrical or loop members 10 and 11 are formed during the stamping operation with indentations or keys 14 and 15 respectively, which are forced into the grooves 12 and 13 85 respectively, thereby effectively retaining the in-turned end portions 7 and 8 against axial movement, while at the same time permitting of relative rotary movement. The indentations or keys are preferably of such dimensions as to frictionally engage the bottom or side walls, or both, of the grooves 12 and 13 90 with sufficient force to hold the frame members 5 and 6 in any desired adjusted positions. 95

The hinge member 9, is preferably of such dimensions that it will maintain the upper portions of the frame members 5 and 6 spaced transversely substantially the correct distance to fit snugly over a clothes line or wire. 100

Referring more especially now to the form of the invention shown in Figs. 4 and 5, it will be noted that substantially the same results are here accomplished in a somewhat different manner. That is to say, instead of providing the in-turned end portions 7 and 8 upon the frame members 5 and 6 with grooves which receive keys or projections carried by the hinge member 9 the construction is reversed in that the end portions 7 and 8 are provided with projections in the form of bights or reverse bends 16 and 17 which are 105 110

formed in the said ends 7 and 8 and which are received in notches or recesses 18 and 19 which are cut into the sides of the cylindrical loop portions 10 and 11 of the hinge member 9, as will be readily understood. These bights or reverse bends 16 and 17 frictionally engage the side walls of the notches or recesses 18 and 19 and serve to hold the frame members 5 and 6 in various set angular positions while at the same time they will prevent the end portions 7 and 8 from moving axially and being withdrawn from the loops 10 and 11.

The form of the invention shown in Fig. 6 is closely analogous to that shown in Figs. 4 and 5 except that instead of providing the reverse bends or bights such as 16 and 17, the end portions 7 and 8 are made somewhat shorter and the extreme ends 20 thereof are turned outwardly through the notches or recesses 18 and 19.

In these two latter forms of the invention the edges 21 of the notches or recesses 18 and 19 serve as stops to limit the angular movement of the frame members 5 and 6 in that the said edges would be engaged by the projections formed by either the bights 16 and 17 or the outturned ends 20, when the said frame members are opened at an angle to substantially 180°. Of course, the angle of such opening may be readily controlled by changing the location of the edges 21 or in other words by making the said notches or recesses 18 and 19 deeper or shallower as circumstances may require.

It will thus be seen that this invention provides a hinge construction for drying forms and the like which may be inexpensively manufactured and which will effectively serve to frictionally hold the form members in any adjusted angular position, while at

the same time holding their inturned end portions against axial movement, relative to the hinge member 9 and thereby prevent the disengagement of the parts.

While several forms of the invention have been illustrated and described, it is obvious that those skilled in the art may vary the details of construction as well as the precise arrangement of parts, without departing from the spirit of the invention, and therefore, it is not wished to be limited to the above disclosure except as may be required by the claims.

What is claimed is:

1. In a drying form, a frame to support the article to be dried, formed with a hinge portion; and a cooperating hinge member encircling the said hinge portion in which the latter may turn, the said hinge parts being formed with interengaging friction-producing means which, while permitting movement of the drying frame, operate to hold the latter in desired position.

2. In a drying form a metal frame shaped to receive the article to be dried and formed with a hinge portion, such hinge portion being made with a projection of reverse bend form; and a cooperating hinge member encircling the said hinge portion of the frame, in which the latter may turn, the encircling hinge member being recessed, and the reversely bent portion of the hinge portion of the frame lying in said recess and having friction-producing engagement with the encircling hinge member whereby, while permitting movement of the drying frame, it will operate to hold the latter in a desired position to which it may be set.

PAUL J. TIMBERLAKE.
